US0D1071900S

(12) **United States Design Patent** (10) **Patent No.:** **US D1,071,900 S**
(45) **Date of Patent:** **** Apr. 22, 2025**

(54) **HEADPHONES**

(71) Applicant: **Shenzhen Xunweijia Technology Development Co., Ltd.**, Shenzhen (CN)

(72) Inventor: **Qibin Mai**, Shenzhen (CN)

(73) Assignee: **Shenzhen Xunweijia Technology Development Co., Ltd.**, Shenzhen (CN)

(**) Term: **15 Years**

(21) Appl. No.: **29/892,521**

(22) Filed: **May 18, 2023**

(51) LOC (15) Cl. **14-01**

(52) U.S. Cl.

USPC **D14/206**; D14/226

(58) **Field of Classification Search**

USPC D14/206, 226, 205, 225; D13/168; 381/380-381, 74, 374, 370; D29/112; 2/209

CLAIM

The ornamental design for headphones as shown and described.

DESCRIPTION

FIG. 1 is a perspective view of headphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict portions of the headphones that form no part of the claimed design.

1 Claim, 8 Drawing Sheets
